UNITED STATES PATENT OFFICE.

MARY A. PATON, OF PARIS, KENTUCKY.

HEAD-DRESS.

SPECIFICATION forming part of Letters Patent No. 338,101, dated March 16, 1886.

Application filed November 21, 1885. Serial No. 183,506. (No model.)

To all whom it may concern:

Be it known that I, MARY A. PATON, a citizen of the United States, and a resident of Paris, county of Bourbon, State of Kentucky, have invented new and useful Improvements in Head-Dresses or Wigs, of which the following is a full and exact description, reference being had to the accompanying drawings, making part of this specification, in which—

10 Figure 1 shows the application of my invention to the head of a lady. Fig. 2 is a front view of the head-dress, and Fig. 3 a perspective view from the under side of same.

15 My invention consists in the combination, with a lace or hair foundation having its outer surface provided with human hair, as in the ordinary construction of wigs and head-dresses, of similar hair secured to the inner side of the foundation, the latter hair to be of sufficient 20 length to extend beyond the edge of the foundation, so as to be combed or brushed in with the top hair, and rolled or turned back therewith, thus entirely hiding the edging of the foundation and imparting to the wig or head-dress a more natural appearance than heretofore attained in the art of making same.

25 The accompanying drawings contain illustrations of my improvement as applied to a lady's head-dress, showing same fashioned into a combination of "bangs," *a*, and "pompadour" *b*. In this instance the under hair is secured to the inner surface of the foundation *c*, at or about the center of the front portion thereof. The width being about equal to that 30 of the pompadour desired, the top hair at each side of the pompadour is brought forward over the edge of the foundation and made to rest on the temples of the wearer, thus forming the bangs above referred to. The hair has a natu-

ral appearance, and can be combed in with 40 the hair of the head and secured with the ordinary fastening thereof. It dispenses entirely with the unsightly net, and does not require any wire or other hard substance to keep it in shape or position. The hair is well 45 ventilated, and being soft is of but little weight; hence it does not hurt the head, but can be worn with the greatest comfort and ease in all kinds of weather. The hair can be dressed on the wearer's head by simply running a comb 50 through it and combing at the sides as though it were the natural hair of the head. If the pompadour *b* is not becoming to the wearer, it can be transformed into beautiful bangs by 55 simply bringing the hair of same to the front and combing down on the forehead with a wet comb.

This invention is durable, as well as light, and when properly placed on the head the closest observer cannot detect it from being 60 the wearer's own natural hair.

Having described my invention, what I claim as new, and desire to secure by Letters Patent, is—

As a new article of manufacture, a head-dress or wig composed of a lace or hair foundation having its outer surface covered with hair in the usual manner, in combination with hair secured to the inner side thereof in such manner that the hair of the two surfaces may 70 be brought together and combed, substantially as described.

In testimony whereof I affix my signature in presence of two witnesses.

MARY A. PATON.
